(57) **CLAIM**

We claim the ornamental design for a coupler for coupling a 3-dimensional model of an item to an articulating member, as shown and described.

DESCRIPTION

FIG. 1 is a first perspective view of the coupler showing a first exemplary embodiment of our new design;

FIG. 2 is a second perspective view, thereof;

FIG. 3 is a top view, thereof;

FIG. 4 is a bottom view, thereof;

FIG. 5 is a rear side view, thereof;

FIG. 6 is a front side view, thereof;

FIG. 7 is a left side view, thereof; and,

FIG. 8 is a right side view, thereof.
